Filed Aug. 5, 1966, Ser. No. 3,360

Term of patent 14 years

(Cl. D26—14)

FIG. 1

FIG. 2

FIGURE 1 is a left side, top and front perspective view of a front panel for a radio cabinet or similar article showing my new design, said panel having a circular opening located therein in which is disposed a grille cloth shaped like a truncated cone and continuous within the boundaries shown, and

FIGURE 2 is an enlarged cross-sectional view taken along line 2—2 in FIGURE 1.

The broken line showing of a representative radio cabinet is for illustrative purposes only.

I claim:

The ornamental design for a front panel for a radio cabinet or similar article, as shown and described.
